UNITED STATES PATENT OFFICE.

ARNOLD O. RUTZ, OF MILWAUKEE, WISCONSIN, ASSIGNOR TO MILWAUKEE GAS
SPECIALTY COMPANY, OF MILWAUKEE, WISCONSIN.

IGNITER-TORCH FOR GAS-STOVES.

1,207,441.

Specification of Letters Patent.

Patented Dec. 5, 1916.

Application filed September 13, 1915. Serial No. 50,511.

To all whom it may concern:

Be it known that I, ARNOLD O. RUTZ, a citizen of the United States, and resident of Milwaukee, in the county of Milwaukee and State of Wisconsin, have invented certain new and useful Improvements in Igniter-Torches for Gas-Stoves; and I do hereby declare that the following is a full, clear, and exact description thereof.

10 My invention refers to igniter torches for gas stoves and it has for its object to provide a simple, economical and effective hood for such torches, which hood in this instance forms part of the stove grid. Heretofore the hood portion of the torch-head has been attached in some manner to said head and constitutes with the head a unitary device to be sold to the trade. This construction not only adds materially to the cost in man-

15 ufacture but under the usual conditions a torch of the ordinary type, in its installation, requires more or less adjustment. This is effected by bending or deflecting by hit or miss methods the delicate tube portion 20 of the torch-head so as to properly aline the firing ports of said head with the burners. Consequently an unsatisfactory operating device will frequently result. With my present improved form of torch head, the 25 shield or hood portion is a separate element and part of the stove grid, and when the head portion of the torch is approximately correctly positioned with relation to the series of burners thereabout, the grid carrying 30 the shield or hood is dropped into place and will engage a portion of the torch-head and press the same slightly downward so as to aline its ports upon a correct horizontal plane, whereby they will discharge upon the 35 several burners. Thus the firing head is to a certain extent self-centering or self positioned when the grid is dropped into position over the burners.

40 A further advantage resulting from my improved arrangement wherein the grid carries the shield or hood is that the weight of the hood is eliminated from the more or less delicate supply tube which carries the flash igniter.

45 In illustrating one example of my improved construction of torch-head attention is called to the fact that I do not limit myself to any specific design of shield in connection with the grid as there are obviously 50 many forms within the knowledge of the

skilled mechanic for carrying out the invention, whereby the function of the hood is assumed by the grid. It should further be understood that in attaching the shield to the grid under ordinary conditions, it would be cast as an integral part thereof, whereby there is comparatively no increase in the expense of manufacturing the grid and in its arrangement in connection with the grid it is only necessary to provide clearance 60 space or firing ports of some type in connection with the wall of the shield, whereby the jet flames will not be interrupted.

With the above objects in view the invention consists in certain peculiarities of construction and combination of parts as set forth hereinafter with reference to the accompanying drawings and subsequently claimed.

In the drawings Figure 1 represents a 75 plan view of a stove grid made in two sections and embodying a shield conforming to my invention, a portion of one of the grid sections being broken away to more clearly illustrate said shield; Fig. 2, an enlarged 80 sectional view of a portion of the grid and shield, the section being indicated by line 2-2 of Fig. 1, and in this view a fragment of the torch-head is shown centered with relation to the shield; Figs. 3 and 4 illustrate similar sectional views of other forms 85 of shield exemplifying my invention with the torch-heads in place.

Referring by characters to the drawings, 1, 1, represent the ordinary grid plates 90 which are fitted over the burners of a gas stove, not shown, the burners being arranged to center at the scrolled openings *a*, four of which are shown. The grid sections are provided with transverse bars 2, 3, which, as 95 shown, are match-jointed at the center of the stove, the bar 2 being provided with a lip portion 2', upon which the bar 3 rests. The construction of these bars, however, forms no part of my invention as they may 100 be supported in various ways and as a matter of fact in some instances the grid is made in one piece. When, however, as shown in Figs. 1 and 2, the grid is made in sections, the central portions of the bars 2 and 3 are 105 each cast with one-half 4 of a torch-head shield *A*.

As shown in Fig. 2, the two-part shield member is formed in cup shape in connection with the bars 2 and 3 and extends 110

downwardly and the lower edges of the walls are formed with firing apertures or ports 5. The shield so formed is adapted to receive any type of burner head B, which 5 burner head is provided with the usual lateral jet apertures 11 and is supported by and supplied with gas from the tube b. The shield extends below the jet apertures in the usual manner, as shown in Fig. 2 10 of the drawings, the burner-head is also provided with a spider c having an upturned outer edge which is adapted to engage the lower edge of the shield and thus center the torch-head B with relation 15 thereto. Hence in assembling the device, the torch-head B is arranged to extend slightly above its ordinary firing plane and when the grid members are dropped into place the lower edge of the shield A will 20 enter the flange of the disk c and thus said burner will be properly centered and pressed downward to the desired horizontal plane, whereby its jet flames will be discharged through the firing apertures 5 25 to the series of gas burners, not shown. By utilizing the disk c, as shown, it will be observed that the torch-head shield will thus be to a certain extent closed, whereby cross-currents of air will be prevented from 30 snuffing out the pilot-light which is kept constantly burning at the tip of the torch-head.

Fig. 3 of the drawings illustrates a form of shield or hood A wherein the firing 35 ports 5' are circular in form and the depending walls of the shield extend below the same a predetermined distance. In this exemplification of my invention the torch-head B is shown provided with an upwardly extended nib e, which centers in a central recess e' that is formed in the upper portion of the shield. Thus when the grid is dropped into place the recess e' coming 40 in register with the nib e will properly align the associated parts of the torch-head with relation to the stove burners. In the 45 form of torch-head B shown in Fig. 3 the pilot-light C is illustrated as being supplied with gas by a separate tube, while in the 50 first form mentioned the tube b supplies both the pilot-light and the jet flames with gas, which supply is increased in a firing 55 operation by suitable valve mechanism, not shown.

Attention is also directed to the fact that in Fig. 3 of the drawings the grid is shown as a single piece and the shield is thus not interrupted centrally or is not halved.

Fig. 4 of the drawings shows still another 60 form of my invention wherein the shield sections 4, 4', are stopped above the firing line of the jet flames and in order to protect said jet flames from cross-currents of air an apron 4" is formed below the lower 65 edge of the shield members and this apron

is connected to said shield portions 4 by webs 4''. The apron portion and main portions 4, and 4', of the shield in this instance are flared outwardly and the juxtaposed walls which are spaced apart to form firing 70 ports are upon different planes, whereby proper protection is insured against air currents which might otherwise interfere with the proper operation of the torch-head. It also follows that in all instances the shield 75 or dome in addition to performing the functions mentioned, serves as a protector for the constantly burning pilot-light of the torch-head against liquids or drippings that might overflow from cooking utensils. 80

In each of the exemplifications shown the shields are circular in form but it is manifest that the grid ribs or bars can be formed with web extensions below the ordinary 85 plane of the grid to produce the desired shield effect and these webs, which will extend down to form the shield, may be polygonal in form or in any other suitable design depending upon the taste of the manufacturer or designer, the essential feature of the invention being the provision 90 whereby some form of hood or shield is associated with the grid in contradistinction to its association with the torch-head.

I claim:

1. A flash igniter comprising the combination with a gas stove having a series of burners and a supporting grid above the burners of an igniter tube having a vertically disposed torch head provided with lateral jet apertures and a shield member carried by and depending from the grid and receiving the torch head, with the lower portion of said shield member disposed below the plane of the jet apertures. 105

2. A flash igniter comprising the combination with a gas stove having a series of burners and a supporting grid above the burners of an igniter tube having a vertically disposed torch head provided with lateral jet apertures, and a depending shield member formed integrally with the grid and receiving the torch head with the lower portion of said shield member disposed below the plane of the jet apertures. 110

3. A flash igniter comprising the combination with a gas stove having a series of burners and a supporting grid above the burners of an igniter tube having a vertically disposed torch head provided with jet apertures, a shield member carried by and depending from the grid, with the lower portion of said shield member disposed below the plane of the jet apertures, and means associated with the shield and torch head for holding the torch head centered within the shield. 115

4. A flash igniter comprising the combination with a gas stove having a series of burners and a supporting grid above the 120

burners of an igniter tube having a vertically disposed torch head, a shield member adapted to receive the torch head, and carried by and depending from the grid, an apertured plate adjustably carried by the torch head and a peripheral flange on the plate adapted to embrace the mouth of the shield to hold said head centered with respect thereto.

10 5. A flash igniter comprising the combination with a gas stove having a series of burners and a supporting grid above the burners of an igniter tube having a vertically disposed torch head, provided with 15 horizontal firing ports and a shield member

for the torch head comprising a pair of vertically alined frusto-conical wall portions, a closure at the top of the upper wall portion, arms connecting the wall portions, and the firing ports of the torch head being disposed 20 between the planes of the adjacent ends of the wall portions.

In testimony that I claim the foregoing I have hereunto set my hand at Milwaukee, in the county of Milwaukee and State of 25 Wisconsin, in the presence of a witness.

ARNOLD O. RUTZ.
